US0D1058621S

(12) **United States Design Patent** (10) **Patent No.:** **US D1,058,621 S**
(45) **Date of Patent:** **** Jan. 21, 2025**

(54) **SPLICABLE CLING FILM CUTTER**

(71) Applicant: **Shenzhen Xinchangtu Technology Co., Ltd.**, Shenzhen (CN)

(72) Inventor: **Min Li**, Shenzhen (CN)

(73) Assignee: **Shenzhen Xinchangtu Technology Co., Ltd.**, Shenzhen (CN)

(**) Term: **15 Years**

(21) Appl. No.: **29/850,156**

(22) Filed: **Aug. 17, 2022**

(51) LOC (15) Cl. **06-06**

(52) U.S. Cl.

USPC **D6/518**

(57) **CLAIM**

The ornamental design for a spliceable cling film cutter as shown and described.

DESCRIPTION

FIG. 1 is a front, right, bottom perspective view of a spliceable cling film cutter, showing my design.

FIG. 2 is a rear, left, top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof; and,

FIG. 8 is an enlarged bottom plan view thereof.

1 Claim, 8 Drawing Sheets
